UNITED STATES PATENT OFFICE.

PASQUALE FICCIO, OF TAMPA, FLORIDA.

SIGN AND INDICATOR.

1,079,754.

Specification of Letters Patent. Patented Nov. 25, 1913.

Application filed April 21, 1913. Serial No. 762,669.

To all whom it may concern:

Be it known that I, PASQUALE FICCIO, a citizen of the United States, and a resident of Tampa, in the county of Hillsboro and State of Florida, have made certain new and useful Improvements in Signs and Indicators, of which the following is a specification.

My invention relates to means for illuminating signs and indicators, especially those carried at the rear of automobiles.

The main object of my invention is to provide a lamp having novel means for throwing the rays upon the registration number.

Other objects and advantages will appear in the following specification and the novel features of the device will be particularly pointed out in the appended claim.

My invention is illustrated in the accompanying drawings forming part of this application in which—

Figure 1 is a perspective view of the device, Fig. 2 is a longitudinal section through the slide case, Fig. 3 is a transverse section through the device, and Fig. 4 is a diagrammatic view showing the arrangement of the circuits.

In carrying out my invention I provide a box or casing 1 of any suitable shape, but preferably a thin rectangular box such as that shown in the drawings. Within the casing are a pair of slidable plates such as those shown at 2 and 3 respectively. These plates are preferably provided with grooves such as that shown at 2^a which are arranged to engage tongues 4^a in the slotted end 4 of the box casing, so as to guide the plates in their movement. The bottom 1^a of the box is provided with an opening 5 in which are pivoted two bell-crank levers 6 and 7 respectively. The upper end of each of these bell-crank levers is connected by means of an arm or a link 8 to one of the sliding plates. In Fig. 2 the arm 8 is shown as being connected to the sliding plate 3. Each plate is connected by means of a spiral spring 9 with a rear end of the box. The short arm of each bell-crank lever is provided with a laterally extending lug such as that shown at 6^a and 7^a, these lugs being arranged to extend through openings in the bottom of the box and to engage spring contacts such as that shown at 10 in Fig. 2. The contacts 10 are arranged to engage stationary contacts such as that shown at 10^a

when the lugs on the arms 6 or 7 are drawn downwardly.

At 12 and 13 I have shown a pair of electric lights, these lights being colored differently and being in circuit with the battery B and with the contacts as shown in Fig. 4.

On the outside of the casing 1 I provide a lamp 14 which is inclosed in a box or casing 15. The front part of this casing is covered with ruby glass 16, while the ends of the casing are closed by green glass panes 17. In the bottom of the box is placed a prism 18 for refracting the rays which pass through the prism at an angle so as to illuminate the plate 19 bearing the registration number 20. This plate may be secured to the case in any suitable manner as by screws 21.

From the foregoing description of the various parts of the device the operation thereof may be readily understood.

Normally the springs 9 hold both the sliding plates 2 and 3 within the box or casing. Suppose now that the automobile is going around a corner and the driver wishes to indicate whether he is going to turn to the right or to the left, so that any one coming up behind him may be warned thereby. He pulls downwardly on one of the levers 6 or 7 by means of a chain or other suitable connection 22, thereby throwing the upper end of the bell-crank lever forwardly and forcing the plate out against the tension of the spring 9. In Fig. 1 I have indicated the slidable plate 2 as being thrown out. On the release of the chain or flexible member 22 the spring 9 will carry the plate back within the box. If it is dark the operator may close the switch S (see Fig. 4) thereby switching on the electric circuit so that when either of the levers 6 or 7 is manipulated the withdrawal of the lug, as for instance 6^a, will permit the contact 10 to engage its contact 10^a thereby lighting the lamp 12. If the other lever is manipulated the lamp 13 will be lighted.

The provision of the casing 15 for the tail lamp 14 provides a warning light at the rear of the device. The green light indicates that the vehicle is passing at right angles to the observer, and it also prevents the light from interfering with the lamps 12 or 13. The prism 18 in the bottom of the casing 15 throws the light downwardly upon the plate 19, which bears the registration

number and keeps this plate constantly illuminated, but this light also does not reach the lamps 12 and 13 and hence does not interfere with their use at night.

5 I claim:

In a sign or indicating device for automobiles, a supporting member, an electric lamp carried thereby, a plate secured to the supporting member beneath the lamp and bearing a registration number and a housing for said electric lamp, said housing com-

prising a top portion, a front portion of ruby glass, end portions of green glass, and a glass prism disposed in and constituting the bottom of said housing, said glass prism 16 being positioned to refract light from the lamp upon the registration member.

PASQUALE FICCIO.
